7662X

A. G. Hull,

Truss.

Patented July 5, 1833.

No. 1.

No. 2.

July 5 1833

45

Amos G. Hull

Letters Patent.

The Schedule referred to in these Letters Patent, and making part of the same, containing a description in the words of the said Amos G. Hull, himself, of his improvement in the surgical instrument called the Throo, to be used in varicose, and in some cases, of general, pleural Hernia:

This improvement is intended particularly for the cure of varicose, which is an enlargement of the blood vessels connected with Spermatic chord, in the application of the Throo to this disease. The object is to compress the enlarged blood vessels, so as nearly to close up the orifice, for which purpose the disease vessels which lie in the cavity of the testis or the bag containing the testicles, must be gathered & raised up under the integuments, and brought opposite the abdominal ring when they may be subjected to pressure by applying the pad directly upon them. The form and dimension of the parts to which the pad is applied in case of varicose, are such that a flat or even concave pad may be used with success. The lower portion of the pad ought to press upon the bone called in books of anatomy, "apatis" at that place where the Spermatic chord runs over that bone, it is essential to the successful application of this instrument, that the degree of pressure made upon the chord should be diminished or increased by the patient according to his sensations in the seat of the disease, it being important to avoid injury to the nerve which it is indispensable, however, to make pressure sufficient to prevent the swelling of these blood vessels, which constitutes the disease. To accomplish this object, a contrivance has been made by this applicant, which is to be used in connection with the instrument for which this application was made, being date, August 10th, 1831, now instrument containing the said instrument, part of the Throo, and of which is the annexed

New York June 5th 1853.

Metaphys
of Mind and Matter
Volume 1

John D. B. Jones

(See on postfolios)

111